UNITED STATES PATENT OFFICE.

GEORGE W. SMITH, OF DAYTON, OHIO.

BURNER.

1,176,175.

Specification of Letters Patent. Patented Mar. 21, 1916.

Application filed December 20, 1915. Serial No. 67,787.

To all whom it may concern:

Be it known that I, George W. Smith, a citizen of the United States, residing at Dayton, in the county of Montgomery and State of Ohio, have invented certain new and useful Improvements in Burners; and I do declare the following to be a full, clear, and exact description of the invention, such as will enable others skilled in the art to which it appertains to make and use the same.

This invention relates to new and useful improvements in burners, and more particularly to oil burners which are adapted for insertion in cook stoves, ranges, heating stoves and furnaces where wood or coal has been used and the same results may be obtained from the use of coal oil in such burner as from natural gas.

20 A further object of the invention is to provide a burner of this character having means for vaporizing the oil and then mixing the same with air at the burner outlet so as to produce a perfect combustion, making a blue blast flame of intense heat without smoke or odor.

Another object of the invention is to provide a device which is simple and durable in construction, inexpensive to manufacture, and one which may be very efficient in operation.

With these and numerous other objects in view, my invention consists of the novel features of construction, combination and arrangement of parts which will be herein referred to and more particularly pointed out in the specification and claims.

In the drawings: Figure 1 represents a plan view of my invention; Fig. 2 is a vertical longitudinal section of the burner; Fig. 3 is an end view; Fig. 4 is a transverse section; and Figs. 5 and 6 are plan and sectional views respectively of the modified form of my invention.

45 In describing my invention I shall refer to the drawings in which similar reference characters designate corresponding parts throughout the several views and in which the numeral 1 designates the support upon which my burner proper is held, which is adapted to fit above the grate in the type of stove in which this invention is placed. The burner is held on the support 1 by legs 2 which are formed integral and depend from the body portion 3 of the burner proper. The body portion 3 of my inven-

tion in the form shown in the first six figures of the drawings is substantially oval shaped, in plan, and has an upwardly projecting flange 4 surrounding the outer edge of the same. The center section of this portion of the burner is enlarged and disposed in a plane below the edge of the same as shown at 5, and one end of the same 6 is formed with a central aperture 7, which is adapted to form a fuel inlet for this device in a manner to be hereinafter more fully described. The portion 3 of the burner is provided adjacent the flanged outer edge 4 of the same with a series or plurality of vertically disposed air tubes 8 extending upwardly through the bottom of the same, and having their upper edge 9 disposed in the same horizontal plane as the upper edge of the flange 4. The vertically disposed air tubes 8 have disposed on their outer surfaces a series of longitudinally extending ribs 10, which are gradually inclined outwardly from the edge of the same to its base. This portion 3 of the burner is provided with a top plate 11, which is substantially oval shaped to conform to the shape of the portion 3 over which it is disposed, and is provided with a series or plurality of openings 12, which are adapted to be disposed over the tubes 8 that are struck upwardly from the body portion 3 of the burner. The openings 12 in the top plate 11 have depending annular flanges 13, surrounding the vertical air tubes 8 when the top plate 11 is in position and spaced therefrom and from the upper surface of the bottom of the portion 3 of the burner, by means of the inclined longitudinally extending ribs 10 on said air tubes. The ribs 10 have their edges inclined downwardly and outwardly, so that when the flanges 13 are engaged therewith, the said flanges will rest against their edges, and will be spaced thereby from the air tubes 8, and likewise will be held a predetermined distance from the upper surface of the bottom of the portion 3 of the burner. By this positioning it will be obvious that a space will be left between the flanges 13 and the tubes 8, so that fuel entering the bottom portion 3 of the burner may escape through the said space. In so doing the same will mingle with air that will flow upwardly through the vertically disposed air tubes 8, and when the fuel is ignited this portion will produce a combustion, and create a blue blast flame of intense heat without

- smoke or odor. The top plate 11 may be also held in position on the top of the bottom portion of the burner by means of projecting lugs 14, upon its outer edge, which position the same from the flange 4 at the outer edge of the base portion of the burner, and also a centering lug 15 which projects from said flange, and coacts with a recess 16 formed in the outer surface of said plate.
- 12 In addition to these means the top plate if desired is secured and firmly held in position by means of bolts or rivets 17 which project downwardly through the top of said plate and are firmly secured to the bottom 15 of the body portion 3 of the burner.
- The central portion of the top plate 11 is surrounded by an oval shaped upwardly projecting flange or rib 18 which is oval shaped, and has adjacent its opposite curved 20 ends pairs of supporting standards 19 and 20, the standard 20 being disposed adjacent the inlet end of the burner and the standard 19 at its opposite end. These standards have their upper surfaces notched as shown 25 at 21 to receive therein a generating coil 22, which is held thereby in spaced relation above the top of the burner. The coil 22 is firmly and securely held in position on the standards 19 and 20 by means of locking members 23, with notched lower faces, that are adapted to be positioned across the 30 top of said coil above the standards 19 and 20 and will hold the same in position as clearly shown in the drawings.
- 35 The burner is provided adjacent its inlet end with a cross pipe 24, which has at the ends of the same a pair of needle valves 25 and 26. The pipe 24 has disposed intermediate its ends an inlet which is adapted to 40 receive the oil that provides the fuel for this burner under pressure. Projecting from the end of the pipe 24 controlled by the needle valve 25 is one end of a coil 22, the said coil extending as has been hereinbefore described, around the top of the burner and spaced above the same, and then back and downwardly as shown at 28, until it terminates in a nozzle 29 controlled by a valve 30 that is disposed adjacent the aperture 7 45 in the inlet portion of the burner. Projecting from the opposite end of the pipe 24, that is the end controlled by the needle valve 26 is a section of pipe 31, that extends forwardly and upwardly and has its opposite end terminating above the central portion 50 of the top plate 11. This central top plate 11 is adapted to form a basin owing to the fact that the same is inclosed by the oval shaped rib 18, which encircles said section.
- 55 The operation of this burner is comparatively simple. Oil under pressure enters the inlet 27 of the pipe 24, and when it is desired to start the burner, the needle valve 26 is opened whereby a certain quantity of 60 oil will be forced through the pipe 31, into

the basin formed by the central portion of the top plate 11 of the burner. This oil is ignited, so that the same will in the course of a few moments heat the coil 22 disposed above the same to the required temperature 70 to vaporize any oil that passes through the same. When the coil 22 is heated the needle valve 26 is closed, and the needle valve 25 is opened whereby the oil, under pressure will be forced through the coil 22 to the 75 nozzle 29 at the end of the same. In circulating around the red hot tube or coil 22 the oil will be vaporized, and on reaching the nozzle 29 which is controlled by the valve 30 and is disposed adjacent the aperture 80 7 in the inlet portion of the burner, the same will be forced therefrom into said entrance of the inlet portion, which comprises an enlarged pipe, and hence upwardly through the burner as has been heretofore 85 described and out through the spaces that are formed between the vertical tubes 8 and the depending flanges 13. The vapor at the outer edge of these spaces is ignited, and owing to the fact that the same mingles 90 at said burner point with the air that comes upwardly through the vertically disposed air tubes a perfect combustion will be formed which produces a blue blast flame of the required intense heat without any smoke 95 or odor.

From the above description the operation of this burner will be easily understood, and it will be seen that by the application of the same, oil under pressure may be easily vaporized, then forced into the burner proper, carrying a certain amount of air with the same at said point and then circulating upwardly through said burner and having at the burner points means for mixing the same 100 with air in an easy, simple and efficient manner. This burner, owing to its simplicity of construction, may be easily and simply made, and furthermore the same may be controlled upon operation of the valves to 105 regulate the same. The burner is especially adapted to be placed in cook stoves, ranges, heating stoves or furnaces where wood or coal has been used.

In Figs. 5 and 6 of the drawings I have 115 shown a slightly different type of burner, which embodies, however, the same principle as illustrated in the first four figures of the drawings. The type of burner shown in these two figures is circular in plan view, 120 having a base portion 35 with an inlet 36 at its bottom, and an upwardly projecting flange 37 around its outer edge. This form of the burner is also provided with a plurality of vertically disposed air tubes 38, 125 having longitudinally extending ribs 39 similar to the type of tube and rib shown in the other form of my invention. This burner is also provided with a circular top plate 40, which has a series of apertures 130

with depending annular flanges 42 surrounding the vertically disposed air tubes 38 and spaced therefrom, in a manner fully shown and described in the other form of my invention. This type of burner operates substantially the same as the one heretofore described, the fuel entering through the inlet 36 and passing upwardly through the space that is formed between the air tube and flanges, whereby the same may mix with air that comes upwardly through the said tubes to make a perfect combustion and a blue blast flame as has been hereinbefore described.

15 From the foregoing description the construction of my improved device, the manner of applying the same to use, and the operation thereof may be readily understood and it will be seen that I have provided a simple, inexpensive and efficient means for carrying out the objects of the invention.

I claim as my invention:

25 1. A device of the class described comprising a burner body having an inlet in its bottom portion, a series of vertically disposed air tubes extending upwardly through said burner body, longitudinally extending spaced ribs on the outer surface of said tubes, said ribs having their outer edges inclined downwardly and outwardly, and a top plate having a series of apertures with depending annular flanges surrounding said air tubes and adapted for engagement with the inclined edges of the ribs whereby the plate is removably supported and the flanges are spaced from the tubes so that the gas may flow therebetween and mix with the air at the ends of said tubes.

30 2. A burner formed of a casting having a series of vertically disposed air tubes ex-

tending upwardly therefrom adjacent its outer edge, a flange on said edge, an inlet in the bottom of the casting, longitudinally extending ribs on said tubes, a top plate 45 with a series of openings adjacent its edge larger than the ends of said tubes, depending flanges on the same surrounding said tubes, and an upwardly projecting rib surrounding the central portion of said top 50 plate.

3. A burner formed of a casting having a series of vertically disposed air tubes extending upwardly therethrough adjacent its outer edge, an integral support for said 55 casting, an upwardly projecting flange on said outer edge, having its extremity disposed in the same horizontal plane with the horizontal plane of the upper edge of said tubes, a centrally disposed depending 60 enlarged inlet in the bottom of said casting, longitudinally extending inclined ribs on the outer surface of said tubes, a top plate correspondingly shaped to the top of said 65 casting, having a series of openings therethrough adjacent its outer edge slightly larger than the upper ends of said tube and surrounding the same, depending annular flanges from said openings surrounding said tubes, and spaced therefrom by the inclined 70 annular ribs, an upwardly projecting rib surrounding the central portion of said top plate, standards projecting upwardly therefrom, and a generator coil supported above 75 the burner by said standards.

In testimony whereof I have hereunto set my hand in presence of two subscribing witnesses.

GEORGE W. SMITH.
